UNITED STATES PATENT OFFICE.

EMIL R. BECKERT, OF CHICAGO, ILLINOIS.

UNDERREAMER.

1,139,096.

Specification of Letters Patent. Patented May 11, 1915.

Application filed December 20, 1913. Serial No. 808,017.

To all whom it may concern:

Be it known that I, EMIL R. BECKERT, a citizen of the United States, residing at Chicago, in the county of Cook and State of Illinois, have invented certain new and useful Improvements in Underreamers, of which the following is a specification.

My invention relates in general to tools for drilling wells, such as oil, gas, and Artesian, and more particularly to underreamers.

In drilling wells it is necessary that the hole should be enlarged in advance of the pipe or casing to a diameter slightly greater than that of the usual shoe at the end of the casing and that of the couplings which connect the successive sections of the casing, in order that the casing may be readily driven downwardly as the work of drilling progresses. This is accomplished by a tool known as an "underreamer", which must be so contracted that it may pass freely downwardly and upwardly through the casing, and when below the lower end of the casing will expand so as to drill the hole to a diameter of the requisite size relatively to that of the casing.

The objects of my invention are to provide an underreamer in which the cutting bits will be so securely supported on the mandrel as to avoid all danger of their accidental detachment; in which the bits when in operative position will directly abut against substantial portions of the mandrel so as to be capable of withstanding the great strains incident to the blows delivered in drilling; in which the bits will automatically yield inwardly should they encounter heavy cavings from the sides of the hole above the bits in action, and which would make it impossible to withdraw the bits in expanded position without this automatic feature; and in which the bits will be automatically folded into a compact position and drawn within the casing by a direct upward pull without necessitating a preliminary movement to unlock the bits from the mandrel.

A further object of my invention is to provide an underreamer, which will be simple and strong in construction, efficient in operation, and durable in use.

My invention will be more fully described hereinafter with reference to the accompanying drawings, in which the same is illustrated as embodied in a convenient and practical form, and in which—

55

Figure 1 is a vertical section, the bits being shown in their operative position; Fig. 2 is a view similar to Fig. 1 showing the bits in folded position within the surrounding casing; Fig. 3 is a perspective view of the 60 pair of bits removed from the mandrel; Fig. 4 is a side elevational view of the lower end of the mandrel, the bits having been removed therefrom; Fig. 5 is an elevational view of the lower end of the mandrel with 65 the bits in position; Fig. 6 is a plan view looking upwardly with respect to Fig. 5; and Fig. 7 is a perspective view of the bits separated and placed side by side.

Similar characters are used to designate 70 similar parts of the several figures of the drawings.

Reference letter A indicates a pipe such as is driven into the ground as the work of drilling a well progresses, and which serves 75 as the casing through which the oil, gas, or water flows upwardly to the surface of the ground.

B designates a shoe secured to the lower end of the pipe A, the lower end of such 80 shoe being beveled outwardly, as shown at b.

C designates a mandrel, which may be provided at its upper end with any suitable means for raising and lowering the same, such means not being shown, as they form 85 no part of my invention but are old and well-known in the art. The mandrel is provided with a chamber c in its lower end, which is preferably rectangular in cross section. Located within the chamber c is a rectangular block D, of a cross section to move with a sliding fit within the chamber, such block being provided on its lower surface with downwardly diverging cam surfaces D' and D''. Secured to the block D, and projecting upwardly therefrom, is a rod d which extends within an opening d' in the portion of the mandrel above the chamber c. A spring E surrounds the rod d and bears at its lower end upon the block D and at its 95 100

upper end against a shoulder e formed in the mandrel around the lower end of the opening d' therein.

- F' and F^2 designate a pair of bits which 5 interlock with each other and are mounted to oscillate within the lower end of the mandrel C . A tubular bushing F extends through alined openings in the overlapped portions of the bits and serves as a pivot 10 upon which the bits may be oscillated. Extending through the tubular bushing F is a rod f which is supported at its ends by the depending side portions C' , C^2 of the mandrel. The bits are provided with upwardly 15 projecting shanks f' and f^2 , respectively, which are curved at their upper ends and fit within the downwardly diverging cam surfaces D' and D^2 of the block D . The bits are provided with concentric curved 20 shoulders G' and G^2 , respectively, above their axes, and such surfaces coöperate with overlying correspondingly curved shoulders g' and g^2 formed in the mandrel at each side of the lower end of the chamber c therein. 25 The bits are also provided with shoulders H' and H^2 , respectively, lying in a plane transverse of the axes of the bits and adapted to engage shoulders h' and h^2 , respectively, formed at opposite sides of the lower 30 end of the chamber c of the mandrel and located intermediate of the curved shoulders g' and g^2 . The bits are also provided with concentric curved shoulders K' and K^2 , respectively, located below the horizontal 35 plane of their axes and adapted to coöperate with correspondingly curved concentric shoulders k' and k^2 , the shoulder k' being located on the bit F^2 in position to coöperate with the shoulder K' on the bit F' , 40 and the shoulder K^2 on the bit F^2 being adapted to coöperate with the shoulder k^2 on the bit F' . In order that the bits may so engage each other as to prevent any relative axial movement, they are provided with 45 lugs L' and L^2 extending in planes transverse to the axes of the bits, which, when the bits are in interlocked engagement as shown in Figs. 3 and 5, overlap each other, the lug L' being received within a recess l' 50 in the bit F^2 intermediate of the shoulder K^2 and the lug L^2 thereon, and the lug L^2 being received in a recess l^2 between the shoulder K' and lug L' of the bit F' .

By reference to Fig. 2 it will be seen that 55 when the bits are oscillated to their contracted position to move within the pipe A , the cutting edges m' and m^2 are prevented from engaging the inner surface of the pipe, by reason of the overlying projections M' and M^2 which bear against the inner surface of the pipe. When, however, the bits are oscillated to their operative position below the end of the pipe, as shown in Fig. 1,

the cutting edges and overlying projections are located in vertical relation so that the 65 cutting edges may engage the material to be cut.

The manner of using and operation of my improved underreamer is as follows: In order to insert the underreamer in the pipe 70 A , the lower ends of the bits are pressed toward each other until their combined cross section is slightly less than the diameter of the pipe. The inward oscillation of the 75 lower ends of the bits causes the upper ends of their shanks f' and f^2 to separate, thereby compressing the spring E through the upward movement imparted to the block D by reason of the engagement of the ends of the shanks with the inclined diverging cam 80 surfaces D' and D^2 . The underreamer may then be inserted in the pipe A and the parts occupy the relative positions shown in Fig. 2. When the underreamer is projected downwardly below the shoe B on the lower 85 end of the pipe A , the bits F' , F^2 are no longer retained in their contracted position by the pipe, and hence are automatically oscillated outwardly by reason of the expansion of the spring E forcing downwardly 90 the block D , which, through the inclined cam surfaces D' and D^2 thereon, forces the upper ends of the shanks of the bits together, as shown in Fig. 1. The cutting edges of the bits are consequently oscillated 95 outwardly so as to drill a hole of a diameter slightly greater than that of the shoe at the lower end of the pipe. When the bits are subjected to the strains incident to impact of the earth, such strains are transmitted to the mandrel through the engagement of the shoulders H' and H^2 with the shoulders h' and h^2 on the mandrel, and also through the engagement of the concentrically curved shoulders G' and G^2 on the 100 bits with the correspondingly curved shoulders g' and g^2 in the mandrel. The strains to which the individual bits are subjected are distributed to both bits by reason of the coöperating concentric pairs of shoulders K' and k' and K^2 and k^2 , so that each bit serves to strengthen the other and to increase its capacity to resist drilling strains. When it is desired to lift the underreamer 105 upwardly through the pipe A , it is merely necessary to exert a direct upward pull, which, through the engagement of the projecting surfaces M' and M^2 on the bits with the lower outwardly flaring end b of the shoe B , oscillates the bits to the contracted 110 position necessary for them to pass into the pipe A , as shown in Fig. 2.

From the foregoing description it will be observed that in my improved underreamer the bits are connected to the mandrel at their 115 strongest portions, so that all danger of the

bits becoming detached from the mandrel, by reason of the breaking of the engaged parts, is avoided. It will further be observed that in my improved underreamer 5 when the bits are in operative position the strains to which they are subjected are directly communicated to the mandrel through the coöperating shoulders on the bits and on the mandrel, and that the strains to which 10 the individual bits are subjected are distributed to both bits by reason of the coöperating shoulders on the bits. It will be further evident that in my improved underreamer the cutting edges when in operative 15 positions project radially farther than any of the overlying parts of the underreamer, and hence there is no danger of any of the parts of the underreamer becoming broken through contact with the materials worked 20 upon, and that even when the bits are worn away through usage and through resharpening the cutting edges will still project radially beyond the overlying portions of the underreamer and thereby protect them 25 from injury. It will also be seen that should the bits become wedged when in expanded position by cavings from above, they would collapse before breakage would occur on heavy upward pulls, inasmuch as the spring 30 E would be compressed and allow the bits to oscillate inwardly, should they be subjected to excessive strains.

While I have described my invention with more or less minuteness and as being embodied in certain precise forms, yet it will be understood that I do not desire to limit myself thereto unduly, or any more than is pointed out in the claims. On the contrary, I contemplate all proper changes in form, 35 construction, and arrangement, the omission of immaterial parts, and the substitution of equivalents, as circumstances may suggest or necessity render expedient.

I claim:—

45 1. In an underreamer, the combination with a mandrel having a chamber in the lower portion thereof, of a pair of complementary overlapping bits extending within the chamber in the mandrel, a pivot rod passing through the overlapped portions of 50 said bits and supported at its ends by the mandrel, concentric coöperating shoulders on the overlapped portions of said bits for transmitting the strains on each bit to the other bit, and means for oscillating said bits to project their cutting edges beyond the vertical plane of the mandrel.

55 2. In an underreamer, the combination with a mandrel having a chamber in the lower portion thereof, of a pair of complementary overlapping bits extending within the chamber in the mandrel, a tubular bushing 60 passing through the overlapped por-

tions of said bits, a pivot rod passing through said bushing and supported at its 65 ends by the mandrel, means for oscillating said bits to project their cutting edges beyond the vertical plane of the mandrel, and coöperating shoulders on the mandrel and bits arranged to contact with each other 70 when the bits are oscillated to outwardly project their cutting edges.

3. In an underreamer, the combination with a mandrel having a chamber in the lower portion thereof, of a pair of complementary overlapping bits extending within the chamber in the mandrel, a pivot rod passing through the overlapped portions of 75 said bits and supported at its ends by the mandrel, means for oscillating said bits to 80 project their cutting edges beyond the vertical plane of the mandrel, concentric coöperating shoulders on the overlapped portions of said bits for transmitting the strains on each bit to the other bit, and coöperating shoulders on the mandrel and bits 85 arranged to contact with each other when the bits are oscillated to outwardly project their cutting edges.

4. In an underreamer, the combination with a mandrel having a chamber in the lower portion thereof, of a pair of complementary overlapping bits extending within the chamber in the mandrel, each of said bits having an upwardly projecting shank 90 extending into a central chamber in the mandrel of less width in the direction of the axis of the bits than the chamber in which the bits extend, a pivot rod passing through the overlapped portions of said bits 95 and supported at its ends by the mandrel, means for oscillating said bits to project their cutting edges beyond the vertical plane of the mandrel, concentric curved shoulders on the bits above their axes formed by the 100 reduced axial width of the shanks, and coöperating shoulders on the mandrel formed by the difference in axial width of the chambers to receive the bits and shanks and adapted to be engaged by said curved 105 shoulders on the bits to transmit strains from the bits to the mandrel.

5. In an underreamer, the combination with a mandrel having a chamber within the lower part thereof, of a pair of bits pivotally supported at the lower end of said mandrel, means for automatically oscillating said bits to project their cutting edges outwardly, a curved shoulder on each bit concentric to and above the axis thereof, 115 shoulders on said mandrel coöperating with said shoulders on the bits to transmit strains from the bits to the mandrels, a lateral shoulder on each bit at one side of its axis, shoulders on said mandrel with which the 20 lateral shoulders on the bits engage when 25

the bits are oscillated to project their cutting edges outwardly, and coöperating shoulders on said bits to transmit strains from one bit to the other.

- 5 6. In an underreamer, the combination with a mandrel, of a pair of overlapping bits pivotally supported on said mandrel and having a common axis of oscillation, means for automatically oscillating said bits to
10 project their cutting edges beyond the vertical plane of the mandrel, and interlocking

lugs projecting radially from the axis of the bits and recesses on said bits to prevent relative lateral movement thereof or individual loss of a bit should breakage occur 15 from abusive use.

In testimony whereof, I have subscribed my name.

EMIL R. BECKERT.
